UNITED STATES PATENT OFFICE.

JAMES R. JARRELL AND A P JARRELL, OF DURANT, OKLAHOMA.

JEWEL SETTER.

Application filed April 3, 1922. Serial No. 549,084.

To all whom it may concern:

Be it known that we, JAMES R. JARRELL and A P JARRELL, citizens of the United States, residing at Durant, in the county 5 of Bryan and State of Oklahoma, have invented certain new and useful Improvements in Jewel Setters, of which the following is a specification.

This invention provides a device for use 10 by watchmakers, instrument-makers, repairers, and others in the setting of jewels in timepieces and other instruments.

It is an object of the invention so to arrange the parts of such a device that the 15 setting of the jewels or stones is facilitated and so that they may be set accurately.

Another object of the invention is to provide a device of this kind with means whereby the shellac or other thermally plastic material used in setting the jewels or stones 20 may be melted or softened by clamping members themselves while the jewel or stone is being set, adjusted, or removed.

When considered in connection with the 25 description herein, the characteristics of the invention will be apparent from the accompanying drawing, forming part hereof, wherein an embodiment of the invention is disclosed, for purposes of illustration.

30 Although the disclosures herein exemplify what now is considered to be a preferable embodiment of the invention, it is to be understood that it is not the intention to be limited necessarily thereto in interpretation 35 of the claims, as modifications and adaptations within the limits of the claims can be made without departing from the nature of the invention.

Like reference-characters refer to corresponding parts in the views of the drawings, of which—

Fig. 1 is a plan view;

Fig. 2 is a section on the line 2—2,

Fig. 1;

45 Fig. 3 is a view of the inner or underside of the table; and

Fig. 4 is a view of parts as seen when the table is omitted.

Having more particular reference to the 50 drawing, 5 designates a base member of any suitable electrically insulating material arranged to be placed on or secured to a bench, work-table, or other suitable support. In the present embodiment, the base member 55 constitutes the top of a box or case 6.

A metallic plate or washer 7 is held on

the inner side of the base by nuts 8 on a threaded shank portion 9 of a metallic standard or supporting member 10, the nuts keeping a shoulder 11 of the standard against 60 the opposite or outer side of the base in such manner as to permit the standard to turn against frictional resistance. The standard projects outwardly from the outer side of the base, and it has near its free or outer 65 end a shoulder 12, from which extends a terminal portion 13 of polygonal shape in cross section and in which is disposed a retaining-screw 14.

The terminal portion 13 of the standard 70 extends into a correspondingly shaped opening in an electrically-insulating table 15, which is supported by the standard in a plane substantially parallel with that of the base and is held thereon by the screw 14. The 75 table is cut away from one of its edges to afford an opening or recess 16 for reception of parts upon which work is being performed and to permit operation of tools on those parts. A slot or elongated opening 17 extends 80 through the table at each side of the recess 16 near the edge of the table.

By suitable fastenings, such as screws 18, metallic holding or clamping members 19 are swingably mounted intermediately of their 85 ends on the outer side of the table, one of those members being disposed on each side of the recess 16. Each of the clamping members has a finger-piece 20 extending outwardly with respect to the table at or near 90 the end opposite to the cutaway edge thereof. At the opposite ends the clamping members have extensions 21 projecting toward each other across the recess 16, and these extensions terminate in inwardly-extending jaws 22. A metallic pin or other suitable part 23 extends from each clamping member through a slot 17 to the opposite or inner side of the table.

A metallic member has a flat or web portion 24 disposed and clamped between the shoulder 12 of the standard and the table, the terminal portion 13 of the standard extending through a correspondingly-shaped opening in the web, so that the member turns 100 with the standard and table. An arcuate spring 25 is formed integrally with and extends from the web 24, and at its free end it engages the part 23 of one of the clamping members.

An arcuate spring 26 at the opposite side 105 of the recess 16 engages the part 23 of the

other clamping member. The springs are tensioned to cause the jaws 22 to close and to hold parts between them. The spring 26 is connected firmly with a metallic web 27 secured to the inner side of the table, and an arcuate metallic contact-piece 28 extends therefrom to the opposite side of the table.

The piece 28 is arranged to be contacted by a metallic spring terminal 29 carried by 10 a metallic support 30 having a threaded shank 31 extending through the base and through a metallic plate or washer 32, the parts being held firmly in place by a nut 33 on the shank.

15 The plates or washers 7 and 32, and thus the standard 10 and support 30, are connected by conductors 34 with any suitable source of electricity, as with a battery 35 in the case 6 as shown.

20 Stops 36 and 37 on the table are arranged to contact with the terminal 29 and limit the turning movement of the table.

As an example of a manner in which the device may be employed advantageously, the 25 setting of a roller-jewel of a watch is explained, the table being in such position that the piece 28 and the terminal 29 are in contact, as in the position shown by Fig. 1, when an electric circuit is closed through 30 the springs 25 and 26 and the jaws 22, and when the recess 16 and the jaws are at the right of the operator. The operator takes the balance-wheel in his right hand and with the thumb and finger of the other 35 hand pressing the finger-pieces 20 opens the jaws of the clamping members 19 until the roller-table of the watch can be inserted between the jaws. Then he places the jewel in the slot in the roller-table, applies gum 40 shellac or other suitable thermally plastic material, and by the heat resulting from the electric current passing through the comparatively high resistance parts between the jaws the material is melted and flows 45 around the jewel. When a sufficient amount of this material has flown around the jewel to hold it securely, the table 15 is turned to the left until the arcuate contact-piece 28 becomes disengaged from the spring terminal 29 and the circuit is broken. The 50 table 15 remains in the latter position until the melted plastic material cools and hardens, whereupon the jaws are released from the work and the work removed. In the 55 event the jewel has not set in proper position, the work again is placed between the jaws and the table 15 is turned to close the circuit and again soften the plastic jewel-holding material and thus permit the

straightening of the jewel. Thereafter, the 60 table 15 again is turned to open the circuit and the work removed from between the jaws. A pallet stone or jewel may be set in a manner similar to that described for a 65 balance-wheel jewel.

Having thus described our invention, what we claim as new, and desire to secure by Letters Patent, is—

1. In a device of the kind described, a rotatably-mounted table, work-holding members thereon in circuit with a source of electricity, and means whereby the circuit is closed when the table is in one position and opened when it is turned to another position.

2. In a device of the kind described, a rotatably-mounted table, work-holding members thereon, an electric-current conductor connected with one of said members, a contact-piece on said table connected with the other of said members, and a member connected with another electric-current conductor arranged to contact with said contact-piece when said table is in one position and to be out of contact therewith when said table is turned to another position.

3. In a device of the kind described, a support, a table rotatably mounted thereon, work-holding members on said table, an electrically-conductive connection between said support and one of said members, a contact-piece on said table connected with the other of said members, and a contact member mounted independently of said table arranged to contact with said contact-piece when said table is in one position and to be out of contact therewith when said table is turned to another position, said contact member and said support being in circuit with a source of electricity.

4. In a device of the kind described, a rotatably-mounted table, work-holding members thereon, springs arranged to impart clamping action to and in contact with said members, a contact-piece on said table connected with one of said springs, a contact member mounted independently of said table arranged to contact with said contact-piece when said table is in one position and to be out of contact therewith when said table is turned to another position, and conductors connecting said contact-piece and said other spring in circuit with a source of electricity.

In witness whereof, we affix our signatures.

JAMES R. JARRELL.
A P JARRELL.
